UNITED STATES PATENT OFFICE.

WILLIAM DENKMANN, OF PHILADELPHIA, PENNSYLVANIA.

IMPROVEMENT IN STEAM-ENGINES.

Specification forming part of Letters Patent No. 40,335, dated October 20, 1863.

To all whom it may concern:

Be it known that I, WILLIAM DENKMANN, of the city and county of Philadelphia, and State of Pennsylvania, have invented a new and useful Improvement in Steam-Engines; and I do hereby declare that the following is a full, clear, and exact description of the construction and operation of the same, reference being had to the annexed drawings, making a part of this specification, in which—

Figure 1 is a perspective view of a reciprocating engine and a steam-generating chamber in connection therewith. Fig. 2 is a vertical cross-section of Fig. 1 through the center of the valve-case E. Fig. 3 is a horizontal section at the red line *a b* of Fig. 2. Figs. 4 and 5 are vertical sections in perspective of the valve-case E. Fig. 6 is a horizontal section of the valve F at the red line *c d* of Fig. 2, with the valve inverted. Fig. 7 is a vertical longitudinal section of the pump C. Fig. 8 is an end view of the same. Figs. 9 and 10 are views at right angles with each other, of the shaft L and its connections on a diminished scale, (shown in connection with the pump C.) Fig. 11 represents the yoke I and tappet *j* on the shaft K, for operating the slide G.

Like letters in all the figures represent the same parts.

The nature of my invention consists in constructing and arranging in connection with the cylinder of a steam-engine a plurality of steam-generating chambers in combination with pumps which force boiling water, to be converted into steam, into the chambers in the form of spray in advance of the time in which the cylinder is opened to receive the steam, and also a peculiarly-constructed valve for feeding the steam into the cylinder and exhausting the same therefrom.

The object of generating the steam in advance of the time in which it is used is to superheat it, similar in effect to superheating the air in my air-engine, which was patented December 16, 1862, but the mode of accomplishing the result is different. The propriety of accomplishing the object becomes very apparent in view of the fact that at each stroke, when the water is injected into the chambers B, the latter become thereby reduced in temperature, and should have sufficient time to regain their highly-heated state before steam is taken from them. This result

I completely accomplish by having a plurality of steam-generating chambers, into which I inject water in regular succession in the order of time in which the steam is taken from each, thus giving to each chamber the length of time to regain its maximum heat, which is expended in withdrawing the steam from all the other chambers to feed the cylinder A.

To enable others skilled in the art to make and use my invention, I will proceed to describe its construction and operation.

A represents a cylinder of a reciprocating engine. As it is constructed in the usual manner, a particular description is not given.

B is one of a series of steam-generating chambers on a diminished scale, which I arrange in a similarly-constructed furnace to those used for steam-boilers.

C is a pump, on an enlarged scale, for feeding the water in the form of spray into the chamber B. There is a similar pump to each chamber of the series. The pump has a feed-pipe, which is secured in the opening *a*.

D is the piston of the pump, which in its forward motion forces the water through the semi-globular screen *b*, causing it to diverge in all directions, so as to strike uniformly the surface of the heated chamber B, by which action it is immediately converted into steam.

c is a check-valve of the pump, and *d* a similar valve of the piston.

E is a circular case through which the cylinder A is supplied with steam. It has openings 1, 2, 3, 4, 5, 6, 7, and 8 for the insertion of one end of steam-pipes, the other ends of which connect separately with the steam-generating chambers B. A portion of one of the pipes is represented in the drawings. The opening 9, near the bottom of the case E, communicates with the steam-passage *e* of the cylinder A, and the opening 10 with the passage *f*, for the purpose of supplying the cylinder with steam and exhausting the same in the manner I will hereinafter describe. The openings 11 and 12 of the case E are steam-exhausts. In the case E there is a rotary conical valve, F, which is operated by means of the slide G, operating the pawls *g h*, which turn the ratchet-wheel H on the stem *i* of the said valve. The slide G is operated by the yoke I by means of the tappet *j* on the shaft K. The yoke and shaft in connection are represented in Fig. 11. The said valve

has an opening, 13, which is extended to near the bottom of the valve, where it communicates with the radial passages 14, 15, 16, and 17, which, as the valve is made to revolve in the direction of the arrow, communicate alternately with the openings 9 and 10 of the case E, and through them with the passages *e f* of the cylinder A, for the purpose of supplying the latter with steam. In a horizontal line with the passages 14, 15, 16, and 17 of the valve F there are intermediate openings, 18, 19, 20, and 21, which take a perpendicular direction upward near the periphery of the valve to about one-half its height, as represented in Fig. 2, and then take an outward direction through the periphery of the valve, and terminate with the openings 22, 23, 24, and 25. The last two numbers being on the opposite side of the valve, as represented in Fig. 2, are not seen. The series of pumps C, which are connected with the generating-chambers B, are operated by the ratchet-shaft L by means of the tappets *h'*, a representation of which is given in Figs. 9 and 10. They are operated consecutively at regular intervals, and the valve F opens the communications with the pipes which lead from the generating-chambers B, to which they are severally connected, after the chambers have all received their first supply of water, beginning with the one into which the water was first injected, and continuing throughout the whole series in the order of time in which they received their supply. Thus each chamber continues to have the same amount of time to regain its maximum heat after it receives its supply of water until the steam is drawn off from it as it takes to fill the whole series of chambers, which suffices to bring the steam up to a high degree of heat, for the purpose of acquiring the amount of pressure which may be desired.

The operation is as follows: After the chambers B have been heated and have received an injection from the pumps C, the valve F being brought with its induction-opening 13 into connection with the opening 1 of the case E, the steam passes through the pipe 1' from the generating-chamber in connection therewith and down the central passage of the valve, and through the radial passage 14, which is then in connection with the opening 9 of the case E, and consequently passes through the passage *e* of the cylinder A into that end of the cylinder and drives the piston forward. Then the valve F being turned in the direction of the arrow in the manner described until the opening 13 of the valve comes into connection with the opening 2 of the case E, the steam flows through the pipe which communicates with the next generating-chamber and the opening 13 of the valve in the same manner as before described, but through radial passage 16, which is now in connection with the opening 10 of the case E, and consequently through the passage *f* of the cylinder A into that end of the cylinder, and the opening 18 of the valve

being in connection with the passage *e* of the cylinder A and the opening 22, which is a termination of the opening 18, being also in connection with the exhaust 11 of the case E, the steam is exhausted from that end of the cylinder and the piston is driven back by the steam let into the other end, as described. The valve is then again turned one-eighth round, which brings the opening 13 into connection with the opening 3 of the case E, and the radial passage 17 with the opening 9 of the case, and thereby with the passage *e* of the cylinder; and the exhaust-openings 20 and 24 being respectively in connection with the passage *f* of the cylinder and the exhaust 12 of the case, the admission of steam into one end of the cylinder and the exhausting of it from the other is again reversed; and by continuing the forward motion of the valve F and bringing the opening 13 into connection with all the openings of the case E from 1 to 8 consecutively the radial passages 14, 15, 16, and 17 of the valve are brought alternately into connection with each end of the cylinder A for the supply of steam, and the exhaust-openings 18, 19, 20, and 21 reversely into connection, as above described, for exhausting the same.

Having thus fully described the construction and operation of the improvement in steam-engines as invented by me, what I claim therein as new, and desire to secure by Letters Patent, is—

1. Combining and arranging the screens *b* with pumps C and steam-generating chambers B substantially as described for the purpose of injecting water in the form of spray uniformly upon the surface of the chambers.
2. The combination and arrangement of the valve-case E and valve F with the cylinder A and a plurality of steam-generating chambers B for the purpose of transmitting the steam from the chambers into the cylinder, substantially as described.
3. Constructing the rotary valve F with the induction-opening 13, in connection with the exit-openings 14, 15, 16, and 17 when combined with and arranged to operate in relation to the case E and cylinder A for the purpose of supplying the latter with steam, substantially in the manner above described.

4. Constructing the valve F with the openings 18, 19, 20, and 21, in connection with the openings 22, 23, 24, and 25 substantially as represented, when made to operate in connection with the passages *e f* of the cylinder A and the openings 11 and 12 of the case E in exhausting the steam from the cylinder, substantially as described.

In testimony that the above is my invention I hereunto set my hand and affix my seal this 14th day of August, 1863.

WILLIAM DENKMANN, [L. S.]
